(57) **CLAIM**

We claim the ornamental design for a remote control unit used in vehicle, as shown and described.

DESCRIPTION

FIG. 1 is a perspective view of a remote control unit used in vehicle, showing our new, original and ornamental design;

FIG. 2 is a front elevational view thereof;

FIG. 3 is a rear elevational view thereof wherein the broken lines define a portion of the remote control forms no part of the claimed design;

FIG. 4 is a right side elevational view thereof;

FIG. 5 is a left side elevational view thereof;

FIG. 6 is a top plan view thereof; and,

FIG. 7 is a bottom plan view thereof.
